(57) **CLAIM**

The ornamental design for a jewelry article as shown and described.

DESCRIPTION

FIG. 1 is a top isometric view of a jewelry article illustrating the new design;

FIG. 2 is a front elevational view thereof;

FIG. 3 is a back elevational view thereof;

FIG. 4 is a right side elevational view thereof;

FIG. 5 is a left side elevational view thereof;

FIG. 6 is a top planar view thereof;

FIG. 7 is a bottom planar view thereof;

FIG. 8 is a top isometric view thereof showing the jewelry article in an alternate position;

FIG. 9 is a top isometric view of the base thereof;

FIG. 10 is a front elevational view of the base thereof;

FIG. 11 is a back elevational view of the base thereof;

FIG. 12 is a right side elevational view of the base thereof;

FIG. 13 is a left side elevational view of the base thereof;

FIG. 14 is a top planar view of the base thereof;

FIG. 15 is a bottom planar view of the base thereof;

FIG. 16 is a top isometric view of a jewelry article illustrating the new design;

FIG. 17 is a front elevational view thereof;

FIG. 18 is a back elevational view thereof;

FIG. 19 is a right side elevational view thereof;

FIG. 20 is a left side elevational view thereof;

FIG. 21 is a top planar view thereof;

FIG. 22 is a bottom planar view thereof;

FIG. 23 is a top isometric view thereof showing the jewelry article in an alternate position;

FIG. 24 is a top isometric view of the base thereof;

FIG. 25 is a front elevational view of the base thereof;

FIG. 26 is a back elevational view of the base thereof;

(Continued)

FIG. 27 is a right side elevational view of the base thereof;
 FIG. 28 is a left side elevational view of the base thereof;
 FIG. 29 is a top planar view of the base thereof; and,
 FIG. 30 is a bottom planar view of the base thereof.
 The broken lines in the drawings are included for the
 purpose of illustrating portions of the jewelry article that
 form no part of the claimed design.

1 Claim, 26 Drawing Sheets
